THERMOSTAT

Filed May 9, 1928

UNITED STATES PATENT OFFICE

NEILSON T. BRANCHE, OF TOLEDO, OHIO, ASSIGNOR TO SURFACE COMBUSTION CORPORATION, OF TOLEDO, OHIO, A CORPORATION OF NEW YORK

THERMOSTAT

Application filed May 9, 1928. Serial No. 276,301.

This invention relates to thermostats and more particularly to a thermostat having a thermal member adapted for positioning within a heating chamber of a heat treating furnace.

It is an object of the invention to provide an instrument of the character indicated which shall be provided with means for damping the operation of the instrument in order to prevent immediate actuation of the 10 instrumentalities under the control of the thermostat upon the opening or closing of a circuit within the thermostat in order to prevent hunting of said thermostatically controlled instrumentalities under relatively 15 small variation in temperatures.

Another object is to provide a thermostat of the character indicated which shall be rugged in construction, relatively inexpensive to manufacture, and which shall be capable of some adjustment in the hands of the 20 ordinary operator.

The single figure of the drawing illustrates the preferred embodiment of the invention, 25 the circuit wires being laid out diagrammatically and some parts being broken away and in section to more clearly illustrate the various constructional features.

In the drawing 10 indicates the main body 30 casting or support to which most of the other parts of the instrument are secured. The lower end 12 of the casting is round in plan and the upper end thereof is of ring like form having a cutaway portion 16 for the convenience in placing the circuit wires. A tubular 35 casing 18 is telescopically positioned over the casting and is secured at its upper and lower end by securing screws 20 which screw into the upper and lower parts 14 and 12 respectively of the casting.

The expansible thermal element is a relatively long tube 22 which is threadedly secured in the lower part 12 of the main body casting. Positioned within the tube 22 and 45 resting on the bottom thereof is a cylindrical rod 24 having a negligible coefficient of expansion such as a quartz rod. Also positioned within the tube 22 and resting on the top of the quartz rod 24 is a push rod 26 of 50 any suitable material having a relatively

small coefficient of expansion. The quartz rod 24 and the rod 26 are of such diameter as to be capable of easy sliding friction within the tube 22 as will be readily understood.

Threadedly secured in the upper end of the 55 push rod 26 is a post 28 having a head between which and the top of the rod 26 is confined a relatively strong coil spring 30. Telescoped over the head of the post 28 is a cap 32 the top of which is pointed to serve as a point 60 abutment bearing.

Appropriately fulcrumed on the casting 10 above the cap 32 is an elbow lever 34. This lever is fulcrumed at the outer extremity of one of its arms as indicated at 36, this arm being extremely short as compared with the other arm of the lever. The pointed end of the cap 32 is adapted to engage with the lever at one side of its fulcrum in order to rock the lever about its fulcrum as will be readily understood. As shown, the point where the cap engages with the lever is provided with a hard steel insert 38 to minimize wear, the top of the cap 32 being preferably also hardened. It will be noted that the long arm of the lever 70 is disposed longitudinally of the casting.

Projecting laterally from the body of the casting and disposed in the path of movement of the upper end of the lever 34 is a lug 40 in which is positioned a switch contact point 42. Positioned in the upper end of the lever 42 is a contact point 44, these two points constituting the two elements of a switch which is normally closed when the thermal tube 22 is cold.

Secured to the casting near its top as by a securing bolt or bolts 46 is a porcelain body 48 having two longitudinally spaced lateral extensions 50 and 52. Secured to the lower lug 52 by a brass securing bolt 53 is a relatively long bi-metal blade 54, the securing means and blade being in the electrical connection with the switch contact point 42 as by a wire 56. Projecting laterally through the lug 50 are two brass bolts 58 and 60. The end of the bolt 58 facing the upper end of the blade 54 constitutes a switch contact point for the blade.

Wrapped around the blade 54 are many 100 turns of fine wire which constitute a heating

- element for the blade, numeral 62 being used to designate the heating element. These wires are not wound directly on the blade but over a thin asbestos sheath which serves the double purpose of an insulator and a means for tempering the heat from the heating element as will be readily understood. A part of the blade above the securing point is not covered by the asbestos sheath and about this exposed part a sufficient number of turns of wire are wound to establish proper electrical connection with the securing bolt 53. The wire at the upper end of the blade is continued over and appropriately connected with the bolt 60 below the bolt 58. When the blade 54 becomes heated it bends and makes contact with its switch point constituted by the end of the bolt 58.
- Secured to the top of the casing 18 is a hard rubber cap 64 in which are mounted three electrical terminals 66, 68, 70. Terminal 66 is wired to connect with the switch contact point 44 at the upper end of the lever 34. Terminal 68 is wired to connect with the bolt 25 60 with which the heating element 62 is also connected, and terminal 70 is wired to connect with the bolt 58 which, it will be recalled, is one element of the switch which includes the blade 54.
- Projecting laterally from the casting 10 is a pin 72 which serves as a stop for confining the lever 34 within a limited range of movement. Secured to the lug 40 opposite the top of the lever is a finger spring 74 which presses 35 against the lever 34 and which tends to open the lever switch.
- Adjustably mounted on the thermal tube 22 is a collar 76. The primary purpose of the collar 76 is to abut against the furnace wall 40 when the thermal tube is inserted through an opening in the wall for projection into a heating chamber whose temperature is to be controlled.
- As previously stated the terminal tube 22 is 45 adjustably mounted in the lower part 12 of the casting 10. A set screw 78 serves to secure the tube in its adjusted position. By screwing the tube into or out of the body 12 of the casting such adjustment as may be necessary to calibrate the instrument is effected. When the tube 22 is turned the cap 32 will be longitudinally adjusted with respect to its abutment at the bottom of the lever 34 as will be readily understood and 50 consequently a lesser or greater expansion as the case may be must take place in the tube 22 before the lever 34 is operated to open or close its switch as will be readily appreciated. To facilitate turning of the tube 22 55 I prefer to secure to the tube at its upper end a collar 80 from which projects a handle 82. By grasping the handle 82 and after loosening the set screw 78 turning the tube 22, the instrument may be readily adjusted 60 within limits without dismantling the in-

strument as will now be readily understood.

In order that the weight of the arm 34 may not cause an appreciable variation in the operation of the instrument when the instrument is horizontally disposed, I provide a suitable external pointer or the like, not shown, to enable the operator to place the instrument in such position that the lever 34 will swing about a vertical axis. 70

Terminals 66 and 68 will be connected with a power line A and terminals 70 and 68 will constitute the terminals of a circuit B which leads to a suitable instrumentality, as for example, an electrically operated valve for controlling the flow of gas or other heating agent, for regulating the heat input to the furnace whose temperature is to be controlled. 75

The operation of the instrument may be briefly described as follows: When the thermal element 22 is inserted in the heating chamber it will expand under the influence of the heat therein. This expansion will cause the push rod cap 32 to recede with respect to the fulcrum 36 of the lever 34. Spring 74 tends to open the lever switch. When the thermostat circuit is open the exterior circuit B is open and consequently the condition of the instrumentality controlled by the circuit B will be changed and such instrumentality 80 allowed to control the flow of fuel or the heat input to the heating chamber. When the temperature within the heating chamber drops the tube 22 will contract and when it has contracted sufficiently the lever switch 85 will again close and current flow through the blade heating element 62. When the blade has become sufficiently heated it swings over and makes contact with its contact point or bolt 58 closing the blade switch and the exterior circuit B. Some current will still 90 continue to flow through the blade heating element 62 but since the switch is closed the main circuit will now be through the blade as a conductor, as will be readily understood. 95 In other words reading from the power line A the current will flow by way of the terminal 66 through the contacting switch elements 44 and 42 constituting the lever switch, through the blade 54, the bolt 58, terminal 70, 100 that lead of power line B which connects with terminal 70, then through the instrumentality connected with the circuit B, then through the other lead of the circuit B to terminal 68 and finally to the power line A. 105 As stated some current continues to flow through the heating element 62 even though the blade switch is closed, the heating element being in circuit with the lever switch. 110

The primary purpose of providing the bimetal blade switch is to render the instrument less sensitive to relatively small differences in temperature change. In other words the blade switch introduces a time lag 115 between the openings and closings of the 120

lever switch and the corresponding openings and closings of the external circuit B to prevent the instrumentality connected with the circuit B from "hunting" as will now be readily understood.

Although I have shown an operative device, still it will be obvious that various changes may be made in size, shape, or arrangement of the parts without departing 10 materially from the spirit of the invention.

What is claimed is:

1. In a thermostat, the combination of a tubular casing, an elongated member removably positioned within said casing, a bell 15 crank lever pivoted on said member and having arms of unequal length, the longer arm of said lever extending longitudinally in said casing and the shorter arm of said lever extending transversely in said casing, a pair of 20 contacts, one of said contacts being held by the elongated member, the other of said contacts attached to the longer arm of said lever for movement to and from its fellow contact by said lever, thermally controlled means carried by said elongated member and extending 25 from one end of said casing for actuating said lever, said means being longitudinally adjustable with respect to said member, and means inserted between said lever and said 30 thermally controlled means for absorbing the differential of the movement of said lever and said thermally controlled means.

2. In a thermostat, the combination of a tubular casing, an elongated member removably positioned within said casing, a fixed 35 contact carried by said member intermediate its ends, elongated thermally controlled means projecting longitudinally from and axially adjustable with respect to said member, a bell crank lever pivoted on said member and having arms of unequal length, the longer arm extending longitudinally of said casing and the shorter arm extending transversely of said casing, a movable contact fixed 40 to the longer arm and adapted to swing to and from engagement with the fixed contact, means inserted between the shorter arm of said lever and said thermally controlled means for absorbing the differential of the 45 movement of said lever and said thermally controlled means, and means tending to keep said contacts in open relation.

3. In a thermostat, the combination of a tubular casing, an elongated member removably positioned within said casing, a fixed 55 contact carried by said member intermediate the top and bottom thereof, a bell crank lever pivoted on said member and having arms of unequal length, the longer arm of said lever 60 extending longitudinally in said casing and the shorter arm extending transversely in said casing, a movable contact fixed to the longer arm of the lever and arranged to swing laterally into and out of contact with 65 the fixed contact, thermally controlled means

extending from said elongated member and longitudinally adjustable therewith for actuating said lever, said thermally controlled means normally holding said contacts in closed relation, and means opposing the force 70 of said thermally controlled means and tending to open said contacts.

In testimony whereof I affix my signature.
NELSON T. BRANCHE.
